(57) **CLAIM**

The ornamental design for a fan, as shown and described.

DESCRIPTION

FIG. 1 is a front, right, and top perspective view of a fan, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right, and top perspective view of the fan of FIG. 1, wherein the legs of the fan are in a curved position.

The broken lines shown in the drawings are included for the purpose of illustrating portions of the fan that form no part of the claimed design.
